MOBILE AMPHIBIOUS CAMPING CAPSULE

Toshihiko Sakow, 82 Copley Ave.,
Teaneck, N.J. 07666

Filed Jan. 24, 1972, Ser. No. 220,554

Term of patent 14 years

Int. Cl. D12—14

U.S. Cl. D12—3

FIG. 6

FIG. 7

FIG. 1 is a top plan view of a mobile amphibious camping capsule showing my new design;

FIG. 2 is a side elevational view thereof;

FIG. 3 is a side elevational view of a modified form thereof;

FIG. 4 is a bottom plan view thereof;

FIG. 5 is a bottom plan view of the form shown in FIGS. 1 and 2;

FIG. 6 is a rear perspective view of the form shown in FIGS. 3 and 5 thereof;

FIG. 7 is a front perspective view of the form shown in FIG. 6 with one cover open; and

FIG. 8 is a rear perspective view of a further modified form thereof.

I claim:

The ornamental design for a mobile amphibious camping capsule, as shown and described.
